VANITY CASE

Filed Jan. 12, 1924

Inventor

RICHARD I. BIESHUNS
By his Attorney Edwin Leisner

UNITED STATES PATENT OFFICE.

RICHARD I. BIESHUNS, OF NEW YORK, N. Y.

VANITY CASE.

Application filed January 12, 1924. Serial No. 685,815.

To all whom it may concern:

Be it known that I, RICHARD I. BIESHUNS, a citizen of the United States, residing at No. 583 West End Avenue, New York city, 5 New York, have invented a new and useful Improvement in Vanity Cases, of which the following is a specification.

My invention relates generally to ladies' vanity cases and has reference more particularly to a type of toilet compact embodied in a container having substantially the appearance and size of a watch case.

Many types of toilet compacts are in general use today and it has been observed that 15 the most objectionable feature found in this large variety of types is the relatively large sizes of the cases used to contain the various articles which go to make up a complete toilet compact.

20 The purpose of the present invention is to overcome the objectionable feature pointed out above, and at the same time to provide an attractive vanity case about the size of a fine watch and having a plurality of skillfully arranged compartments adapted to contain face powder, rouge, lipstick, perfume, mirrors and puffs. I accomplish this purpose by means of a compact and case of the character, hereinafter fully described 25 and illustratively exemplified in the accompanying drawings, in which;

Figure 1 is a perspective view of my improved vanity case showing the parts in open and detached positions; Figure 2 is an 30 end elevational view of the case and Figure 3 is a transverse sectional view through the same showing the parts in closed positions.

Referring to the drawing, 10 designates a 35 box case of thin metal material having the general appearance and size of a watch case. The box comprises a relatively thin annular edge portion 11 which is curved and tapered outwardly towards the axis of the case to provide a bezel 12 on both faces. The openings 13 and 14 on opposite faces, respectively, formed by the bezels 12 are provided with covers 15 having spring actuated hinges 16 and similarly operated catches 17 which release either cover by slight pressure of a 45 finger against the exposed portion of the catch. The covers 15 are slightly convex in shape to carry out the general curve of the bezels 12. Integral with the inner edges of the bezels 12 and arranged within the body 50 of the case are two inwardly curved partitions 18 and 19 which virtually divide the

case into three compartments 20 21, and 22, the latter thereof being circumscribed by the edge portion 11, bezels 12 and partitions 18 and 19.

At a point in the periphery of the edge portion 11, hereinafter referred to as the top of the vanity case, the material is disposed outwardly in a radial direction to provide a neck 23 having a threaded bore 24 in communication with the intermediate chamber 22. This chamber or compartment is intended to contain liquid perfume which is applied by means of a stopper 25. The stopper 25 according to the present invention 60 comprises a tubular stem 26, composed of metal or other suitable material, having an externally threaded portion 27 adapted to be adjusted over the threads of the bore 24. The upper end of the stem 26 is laterally 70 flanged and abuts the end of the neck 23 when the stopper is completely inserted in the chamber. The bore at the inner projecting end of the tubular stem 26 is preferably threaded and receives a tapered glass 75 or metal appliance 28 which dips into the perfume and when removed from the case is used to apply the liquid adhering to the projection. Adjacent the inner end of the stem 26 the bore is provided with a closure or partition 29 which entirely separates the upper 80 interior portion of the stem from communication with the perfume chamber. The upper free end of the stem 26 is provided with a bayonet slot 29 to receive a pin 30 projecting from the side wall of a small metal cap or inverted cup 31 containing an adjustably mounted lip or eyebrow pencil 32, the pin 30 being arranged in an inclined slot 33 in the side wall of the cup and having a projecting 90 prong to engage with the pencil 32 for purposes of adjustment.

Further appointments of the compact comprise separate mirrors 34, one thereof being attached or otherwise mounted on the 100 inside face of both cover members 15. A powder cake 34' is carried by the face of partition 19 and a quantity of rouge paste 35 is seated against the face of the partition 18, and in each space between the mirrors and the powder and paste, a separate powder puff 36 is held as shown in Figure 3. Any type of supporting means may be utilized to hang or otherwise carry the case and for purposes of illustration I have 110 shown a pair of rings 37 loosely attached to the edge portion 11 at opposite sides of the

neck 23, the rings being adapted to receive the end of a neck ribbon or chain.

From the foregoing, it will be noted that the present invention contains substantially all of the toilet requisites necessary for a complete facial makeup, and that each article is readily accessible without disturbing any other part of the compact. The double mirrors make it possible for the user 10 to use either the rouge or the powder by simply placing the case in the palm of the hand with the upper part or neck disposed towards the fingers, thereafter releasing the cover which will swing to upright position 15 and expose both the mirror and rouge or powder.

Having now described the present invention what I claim and desire to secure by Letters Patent is:

- 20 1. A vanity case, including an intermediate receptacle having a neck portion and opposite indented side walls, covers for the indented walls, a stopper for said neck portion including a projection adapted to extend into the interior of said receptacle, and a pencil member adjustably mounted in the outer end of said stopper.
- 25 2. A vanity case, as claimed in claim 1, in which the inside surfaces of said covers are provided with mirrors and the opposite faces of the indented walls are provided with powder and rouge cakes, in combina-

tion with a powder puff enclosed in each compartment having a cover, substantially as described. 25

3. A vanity case, as claimed in claim 1, in which the covers are hinged to said receptacle at points opposite the said neck portion, and means for holding and releasing said covers, substantially as described. 40

4. A vanity case, as claimed in claim 1, in which the receptacle further comprises a watch shaped case having curved bezels disposed on opposite faces thereof, said cover members being hinged to said bezels 45 at points opposite to said neck portion.

5. A vanity case, as claimed in claim 1, in which the stopper comprises a tubular member adjustable in said neck portion and having a bayonet slot in its upper end, 50 a tapered member adjustable in the opposite end thereof, said pencil including a lipstick holder comprising a cup member provided with an inclined slot and insertable in the open end of the tubular member, a lipstick 55 for said holder, and a pin engaged with the stick at one end and projecting through the inclined slot to be engaged in the said bayonet slot at its outer end.

In testimony whereof, I have signed my 60 name to this specification this 7th day of January, 1924.

RICHARD I. BIESHUNS.
